(57) **CLAIM**

The ornamental design for a mini-keg growler, as shown and described.

DESCRIPTION

FIG. 1 is a front perspective view of a mini-keg growler showing my new design;

FIG. 2 is a right side view thereof, the left side view being a mirror image;

FIG. 3 is a rear view thereof;

FIG. 4 is a top view thereof; and,

FIG. 5 is a bottom view thereof.

The broken line showing in the figure drawings are included for the purpose of illustration and form no part of the claimed design.
